(57) **CLAIM**

I claim the ornamental design for a line fishing device with fish strike indicator, as shown and described.

DESCRIPTION

FIG. 1 is a perspective view of a line fishing device with fish strike indicator, showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines showing water and a strike light in FIG. 1, and text in FIGS. 2-4, depict environmental matter and form no part of the claimed design.
